REMOVAL OF INORGANIC MATTER FROM
PETROLEUM RESIDUAEdward M. Hughes, Chester, Pa., assignor to Sun
Oil Company, Philadelphia, Pa., a corporation
of New Jersey

Application November 27, 1948, Serial No. 62,371

4 Claims. (Cl. 196—40)

1

This invention relates to the treatment of petroleum residual oils for the purpose of removing inorganic matter and reducing the ash content. The invention more specifically relates to a method of treating petroleum residua which contain alkaline naphthenates, whereby the naphthenates are neutralized and the resulting salt is obtained in the form of relatively large crystals which may readily be separated from the treated oil.

In refinery practice it is customary to subject the crude petroleum to a topping operation wherein the lower boiling fractions such as gasoline, kerosene and gas oil are distilled off and then to treat the reduced crude with an alkali, such as caustic soda, preliminary to subjecting it to further distillation under vacuum to remove the lubricating oil fractions. Treatment of the reduced crude with alkali converts any naphthenic acids which are present into alkaline naphthenate soaps. In the subsequent vacuum distillation step the alkaline naphthenates do not distill but rather remain in the bottoms or residuum from the operation in admixture with high boiling hydrocarbons and asphaltic material. Consequently, the residuum product will have a high ash or inorganic content which reduces its value for use as fuel oil. For example, in the practice of a process of this type such as described in Pew Patent No. 1,761,153, it has been found that crude petroleum of the naphthenic base type will yield a residuum having an ash content generally of the order of 2-3%. However, when the residuum is utilized as fuel oil, it is necessary or desirable that it have an ash content below 0.20% and preferably below 0.10%. Some means of de-ashing the residuum is therefore necessary in order to render it fit for commercial use as a fuel.

While various proposals have been made for reducing the inorganic content of residual stocks, the difficulty or expense involved in practicing the proposed methods commercially has limited their usefulness. Removal of the inorganic matter is complicated by the fact that such residual oils have great emulsion-forming tendency, even after the alkaline naphthenate soaps have been converted by means of mineral acid into naphthenic acids and inorganic salt. Consequently, neutralization of the soaps followed by extraction of the salt with water has been found to be more or less unsuccessful. Water extraction of the salt may be accomplished in some instances by employing selected deemulsifying agents but this adds to the expense of the operation.

2

According to the present invention, the inorganic content of a petroleum residuum which contains alkaline naphthenates is effectively reduced by treating the residuum with sulfuric acid in the presence of water under certain conditions as hereinafter described, and then dehydrating the mixture, whereby the sulfate salt resulting from the neutralization of the naphthenates is obtained in the form of relatively large crystals. 10 These crystals can then be separated readily from the treated residuum by gravity settling or filtration or in any other suitable or convenient manner.

15 Description of the invention will be made with reference to the accompanying drawings which are diagrammatic flowsheets illustrating two procedures for practicing the invention.

20 Referring first to Figure 1, the heavy residuum to be treated enters the system through line 10. A typical refinery product of this type, derived from naphthenic base crude, may have properties as follows:

S. U. visc. at 210° F.=3000-6000

A. P. I. gravity=10-11

25 Ash content=2-3%

The heavy residuum is introduced into the system at an elevated temperature which is at least above 150° F. and preferably above 200° F. For example, the temperature of the residuum entering line 10 suitably may be within the range of 250-550° F., although still higher temperatures may be used if desired.

30 Aqueous sulfuric acid having an H₂SO₄ content within the range of 60-67% by weight is introduced through line 11 into the stream of residuum in amount sufficient to neutralize or substantially neutralize the alkalinity or naphthenate soap content. It is preferable that the amount of acid used be at least sufficient to approach complete neutralization without exceeding the amount required for that purpose, but it is of course not necessary that exact neutrality be reached. Any part of the naphthenate soaps which is not neutralized will remain in the residuum during the subsequent steps of the process and will result in a higher ash content of the product.

35 The combined streams from lines 10 and 11 pass into a mixing device 12 to insure effective mixing and neutralization. Mixer 12 is illustrated as an orifice type mixture, although any other suitable type of mixer may be employed. The mixture is maintained during the neutralization step under sufficient pressure to prevent vaporization of water, this being accomplished by means of a

back pressure relief valve 14 in the outlet flow line 13 from the mixer. It is important that the water be maintained in liquid phase during the neutralization step in order that the operation will result in the formation of salt crystals of relatively large size.

The next step in the process comprises evaporating water from the neutralized residuum. Assuming that the residuum has entered the system at sufficiently high temperature, evaporation of the water may be effected simply by reducing the pressure as by means of valve 14 and directly introducing the mixture into a flash tower 15 from which water vapor passes off through overhead line 16. In cases where the temperature of the residuum is not sufficient to cause vaporization of the water, the residuum from mixer 12 first may be passed through a suitable heater (not shown) and then introduced into flash tower 15.

The dehydrated residuum leaving the flash tower through line 17 contains salt crystals of relatively large size which may be separated from the residuum in any suitable manner. As shown in Figure 1, the hot residuum may be sent to a settling tank 18 and therein permitted to settle for sufficient time to reduce the ash content to the desired value. If desired, the hot residuum may be admixed with light fuel oil or other hydrocarbon fraction of relatively low viscosity before entering settling tank 18 in order to accelerate the rate of settling of the salt particles, although this is not essential if the acidification step has been carried out under the conditions above described and the temperature in the settling tank is sufficiently high to prevent excessive viscosity. The de-ashed product may be withdrawn from tank 18 at an upper level 19. Salt may be removed from the bottom intermittently as by occasionally drawing off the de-ashed residuum layer above the salt and scraping the salt out or flushing it out with hot water; or it may be removed continuously, for instance, in the form of a concentrated slurry of salt and residuum.

It is important in practicing the invention according to the process of Figure 1 that the strength of the sulfuric acid used be within the range of 60-67%. When the strength substantially exceeds 67%, the resulting salt particles will be of extremely fine form so that separation by gravity will not take place to any practical extent. Even when the process is practiced with a filtration step in place of the gravity settling, removal of the fine salt particles to the desired degree is difficult to achieve in commercial operation. On the other hand, when acid of a strength substantially below 60% is used, difficulties will be encountered due to foaming within flash tower 15. The acid strength thus should lie within the range of 60-67% H_2SO_4 by weight and preferably should be about 65%.

Figure 2 illustrates a modified form of the process wherein the residuum is first mixed with water and then with concentrated sulfuric acid in amount sufficient to substantially neutralize the naphthenate soaps. In practicing the invention in this form, the proportion of water to sulfuric acid employed should be such as to be equivalent to an acid strength of 60-67% H_2SO_4 by weight. In other words, if the water and sulfuric acid were premixed with each other before contacting the residuum, the resulting acid solution would have a strength of 60-67%.

It appears that at least in some cases practice of the process according to Figure 2 is still more effective in securing a low ash content product.

Referring to Figure 2, water is introduced in the proper proportion through line 31 into the hot residuum flowing in line 30 and the two are mixed in mixer 32. The mixture flows through line 33 and meets a stream of concentrated sulfuric acid from line 34, the amount of acid being proportioned to substantially neutralize the alkaline naphthenates in the residuum. Mixing is again effected by means of a second mixer 35. The neutralized mixture passes through line 36 and back pressure relief valve 37 and thence to flash tower 38 from which water vapor is removed through overhead line 39. The dehydrated salt-containing residuum is withdrawn through line 40 and, as illustrated in this case, may be sent to a filter 41 which separates the salt crystals and yields a product of low ash content. For commercial operation filter 41 suitably may be of the continuous rotary pre-coat type which is well known to the art.

The following examples are illustrative:

25

Example I

The petroleum residuum used in this example was obtained by treating a reduced crude of naphthenic base origin with caustic soda and then distilling off the lubricating oil fractions under vacuum. It had an S. U. viscosity at 210° F. of 3200. 2000 g. of the residuum was heated to 200° F. and then was mixed with 40.5 ml. of aqueous sulfuric acid having an H_2SO_4 content of 65%, this amount being required for approximately complete neutralization. The mixture was heated to about 400° F. under atmospheric pressure to effect dehydration. The dehydrated material was permitted to stand overnight at a temperature of about 300° F. to separate the salt crystals. The oil layer was tested for ash content, with results as follows:

	Per cent
Original ash content	2.40
15 Ash content after settling overnight	0.08

Another run was made under similar conditions except that the H_2SO_4 content of the aqueous sulfuric acid employed was 69.7%, 40.5 ml. of the acid being employed to approximately neutralize 2000 g. of the residuum.

	Per cent
53 Ash content after settling overnight	1.55
These results show that acid of 65% concentration was effective in producing salt crystals of relatively large size whereas acid of 69.7% concentration was ineffective for this purpose.	

Example II

In this example, the petroleum residuum was mixed first with water and then with the proper amount of concentrated sulfuric acid to effect neutralization, the amount of water and concentrated acid being so proportioned as to be equivalent to acid of about 65% concentration. More specifically, to 1000 g. of residuum, 6.2 ml. of water was added and mixed at a temperature of 200° F., and then 14.3 ml. of 93.2% sulfuric acid was mixed in at about the same temperature. The resulting mixture was heated to evaporate the water and was permitted to stand at about 300° F. Ash content tests were as follows:

	Per cent
Original ash content	2.40
75 Ash content after settling 4 hrs.	0.08

As shown by the preceding examples, the process may be practiced either by adding the acid as an aqueous solution of proper concentration (60-67% H₂SO₄) or by first adding water and then concentrated acid in the proper proportions. It is not permissible, however, to add concentrated sulfuric acid, or acid having a concentration substantially above 67%, before the addition of the water, for this will result in the formation of such small salt crystals that separation by settling or filtration will be rendered impracticable.

Having described my invention, what I claim and desire to protect by Letters Patent is:

1. Method of treating petroleum residuum containing alkaline naphthenates to remove inorganic matter which comprises mixing the residuum at an elevated temperature with water and H₂SO₄ under sufficient pressure to maintain the water in liquid phase, the amount of H₂SO₄ employed being sufficient only to substantially neutralize the residuum and the proportion of water to H₂SO₄ being equivalent to an acid strength of 60-67% H₂SO₄ by weight, said H₂SO₄ being added to the residuum not before the addition of the water, then vaporizing water from the residuum, thereby forming salt crystals of relatively large size, and separating said crystals from the treated residuum.

2. Method of treating petroleum residuum containing alkaline naphthenates to remove inorganic matter which comprises mixing the residuum at an elevated temperature with aqueous sulfuric acid having an acid strength of 60-67% H₂SO₄ by weight under sufficient pressure to maintain the water in liquid phase and in amount sufficient only to substantially neutralize the residuum, then vaporizing water from the residuum, thereby forming salt crystals of relatively large size, and separating said crystals from the treated residuum.

3. Method of treating petroleum residuum con-

taining alkaline naphthenates to remove inorganic matter which comprises mixing the residuum at an elevated temperature with a small amount of water as hereinafter specified, then adding to and mixing with the residuum, while at an elevated temperature and under sufficient pressure to maintain the water in liquid phase, concentrated sulfuric acid in amount sufficient only to substantially neutralize the residuum, the proportion of total water to H₂SO₄ being equivalent to an acid strength of 60-67% H₂SO₄ by weight, then vaporizing water from the residuum, thereby forming salt crystals of relatively large size, and separating said crystals from the treated residuum.

4. Method of treating petroleum residuum containing alkaline naphthenates and having an ash content in excess of 2.0% to remove inorganic matter which comprises mixing the residuum at a temperature above 150° F. with aqueous sulfuric acid having an acid strength of about 65% H₂SO₄ by weight under sufficient pressure to maintain the water in liquid phase and in amount sufficient only to substantially neutralize the residuum, then vaporizing water from the residuum, thereby forming salt crystals of relatively large size, and permitting the mixture to stand at a temperature above 150° F. for a time sufficient to settle out most of the salt and reduce the ash content of the residuum layer to less than 0.20%.
